TOWEL DISPENSING CABINET

Rudolph G. Birr, Lombard, and Albert C. Grunwald, River Forest, Ill., assignors to Steiner Sales Company, Salt Lake City, Utah, a corporation of Utah

Original application August 17, 1938, Serial No. 225,398. Divided and this application December 23, 1940, Serial No. 371,344

4 Claims. (Cl. 312—38)

This invention relates to improvements in dispensing cabinet constructions, including a door which is opened when servicing or loading the cabinet with a supply of fresh toweling, and to means for hinging the door and for holding it open during servicing.

This application is divisional of copending application Serial No. 225,398, filed August 17, 1938, now Patent Number 2,255,609.

The main object of the invention herein is to provide a specific door hinging scheme for doors, and also to provide a hinging scheme particularly applicable to an upwardly opening door for a towel dispensing cabinet. A feature is the means for automatically holding the door in open position, and another feature relates to the manner of hinging a door to the sides of a cabinet in a manner to have the door swing to a position entirely above the cabinet when in open position. This invention provides a hinging scheme and structure which is invisible when the door is closed.

Another feature of the invention is the use of two brackets, each of which is attached by one portion rigidly to the door and each of which is pivoted by another portion to the inner side of a lateral wall of the cabinet.

Objects, features and advantages of the invention will be disclosed in the description of the drawing, and in said drawing the single figure is a vertical transverse section with the door closed and with the upper door shown in dotted lines in open position, to illustrate the action of the hinging means.

In the drawing, the numeral 1 generally designates the outer casing having side walls 2 and a rear wall 3. Numeral 10 indicates an upper door or cover which forms part of the top and closes about one-half of the front opening.

It is to be noted that by making the upper door form a part of the top wall of the cabinet, as well as part of the front wall of the same, and by using the type of hinge herein and placing it as shown, the door when fully open is caused to occupy a position entirely above the upper surface of the top of the cabinet, and the hinging means is invisible when the door is closed.

In this embodiment of the invention there is an inner unit which is detachably secured in the outer casing. The scheme for attaching this unit is covered in a copending application.

A feature of this invention is the manner in which the upper door 10, or any door laterally, upwardly or downwardly swinging, is so hinged by a hinge which is invisible when the door is

closed that the door when swung to full open position lies either entirely to one side, entirely above, or entirely below a cabinet.

The top door is hinged by a pair of arcuate members generally designated 40, each having one end 41 fixed as by welding to the inner surface of that part of the upper door which forms a part of the top wall of the cabinet. The remaining top wall of the cabinet is indicated by the numeral 42. By this arrangement the meeting point 43 of the front of the top wall 42 with the rear edge of the top-forming portion 44 of the door 10 occurs at a point intermediately of the front and rear surfaces of the cabinet. This point is shown almost midway between the front and the rear, but the arrangement is such that when the door is open, as shown in dotted lines in the figure, the whole door is not only moved upwardly to lie entirely above the cabinet, but by the hinging means it is brought rearwardly so that it does not project so far forwardly of the front plane of the cabinet. Each arcuate hinging member has a cross extension 46 having its inner end pivoted as at 47 to the inner side of the side wall of the outer casing. The members 40 are formed to be light in weight and can be formed by pressing or molding. This pivotal point, it is noted, is placed rearwardly of the meeting line 43. In the case of the right-hand member, that is, the right-hand member 40 as viewed in Figure 1, this member is in this instance provided with an extension 48 which serves as a latching extension engageable with a flange-stop 50 carried by an arm 51 pivoted as at 52 to a bracket 53 fixed to the inner side of the casing, and yieldably pressed by means of spring 54 against a stop 55 on the casing. The spring connects at one end with a lateral extension of arm 51 and at the other end with a lateral extension of the bracket 53.

The inner end of the arm 48 acts, as the door is opened, to engage the element 50 and by a wiping motion to swing the arm 51 to the right. After the extension 48 has passed the top of the element 50, the spring again moves the arm 51 to the position shown in the drawing, and the extension 48 is disposed on the top of the latch 50. The stop 55 performs the double function of limiting inward motion of the arm 51 and upward motion of the extension 48. If element 55 is not used, however, the rear end 56 of the door could engage the top surface of the wall 42 as a stop.

It is believed broadly new to hinge a door by two members, each rigidly attached to the door and pivoted to a wall of the cabinet for which the

door forms a closure, irrespective of the forms of the members. Nevertheless, the specific form shown herein is also claimed because the arcuate-cross-arm construction is particularly adaptable for so pivoting the door that it not only swings clear of the cabinet, but is shifted bodily rearwardly as a result of the relation of the elements 41, 47 to the cabinet and to the door. The conception of the hinges or pivots herein in relation to a closure element which forms parts of two different sides of a cabinet is also believed to be new.

It will be understood that the door-latching mechanism is not required at the opposite side of the cabinet (not shown).

We claim as our invention:

1. A cabinet, a door for the cabinet, a pair of door-hinging members, one pivoted to each corresponding side wall of the cabinet, each member being immovably secured to the door, a pivoted latch member on the cabinet, and means carried by one of said members adapted to engage and move the latch as the door is opened and thereafter engage the latch to hold the door in open position.

2. A cabinet, a door for the cabinet, a pair of door-hinging members, one pivoted to each corresponding side wall of the cabinet, each member being immovably secured to the door to form a hinge for the door, a pivoted latch member on the casing, means carried by one of said members adapted to engage and move the latch as the door is opened and thereafter engage the latch to hold the door in open position, said door forming the front and part of the top of the cabinet and said members being pivoted at points rearwardly of the meeting line of the rear part of the top and the door of the casing whereby when said door is latched in open position it lies entirely above the cabinet, and whereby the door is shifted bodily in a direction toward its pivoted points.

3. A cabinet having an outer casing, said cas-

ing having a wall forming part only of one side of the cabinet, a door having a portion cooperating with said wall to complete formation of that side and having another portion which closes the front of the cabinet, hinging means for the door comprising a pair of arcuate members, each having one end fixed to the door and having a cross extension having its inner end pivoted to the outer casing, a latching member yieldably urged to latching position and having a surface engageable by the cross extension of one of said arcuate members as the door is opened, to move the latch away from latching position, means engageable by said cross extension for limiting opening movement of the door at a predetermined position, and means on said latching member between which and said limiting means the extension and therefore the door is held against movement in either of two opposite directions.

4. A cabinet having an outer casing, said casing having a wall forming part only of the top, a door having a portion cooperating with said wall to complete formation of said top and having another portion which closes the front of the cabinet, hinging means for the door comprising a pair of arcuate members, each having one end fixed to the door and having a cross extension having its inner end pivoted to the outer casing, a latching member yieldably urged to latching position and having a surface engageable by the cross extension of one of said arcuate members as the door is opened to move the latch away from latching position, means engageable by said cross extension for limiting opening movement of the door at a position over the cabinet, and means on said latching member between which and said limiting means the cross extension and therefore the door is held against movement in either of two opposite directions.

RUDOLPH G. BIRR.
